[57] CLAIM

The ornamental design for an eyewear retainer, as shown and described.

DESCRIPTION

FIG. 1 is a left side elevational view of a first embodiment of an eyewear retainer showing my new design, the right side being a mirror image thereof;

FIG. 2 is a top plan view thereof;

FIG. 3 is a cross-sectional view of the central portion thereof;

FIG. 4 is a left side elevational view of a second embodiment of an eyewear retainer showing my new design; the right side being a mirror image thereof;

FIG. 5 is a top plan view thereof;

FIG. 6 is a cross-sectional view of the central portion thereof;

FIG. 7 is a left side elevational view of a third embodiment of an eyewear retainer showing my new design, the right side being a mirror image thereof;

FIG. 8 is a top plan view thereof;

FIG. 9 is a cross-sectional view of the central portion thereof;

FIG. 10 is a left side elevational view of a fourth embodiment of an eyewear retainer showing my new design, the right side being a mirror image thereof;

FIG. 11 is a top plan view thereof;

FIG. 12 is a cross-sectional view of the central portion thereof.

The human head shown in broken lines is for illustrative purposes only and forms no part of the claimed design. The specific length of the eyewear retainer is indeterminate, shown by a break and brace bracket, and is not disclosed.
